(57) **CLAIM**

The ornamental design for a fence, as shown and described.

DESCRIPTION

FIG. 1 is a front perspective view of the fence;

FIG. 2 is a top plan view of the fence of FIG. 1;

FIG. 3 is a front elevational view of the fence of FIG. 1;

FIG. 4 is a right side elevational view of the fence of FIG. 1;

FIG. 5 is a rear elevational view of the fence of FIG. 1;

FIG. 6 is a left side elevational view of the fence of FIG. 1;

and,

FIG. 7 is a bottom plan view of the fence of FIG. 1.

The broken line showing the middle section of the fence in
FIG. 1 is illustrative of environmental structure only and
forms no part of the claimed design.
